US0D1033776S

(12) **United States Design Patent** (10) **Patent No.:** **US D1,033,776 S**
(45) **Date of Patent:** **** Jul. 2, 2024**

(54) **WATER TANK FOR ROBOTIC VACUUM CLEANER**

(71) Applicants: **Yunjing Intelligence Technology (Dongguan) Co., Ltd.**, Dongguan (CN); **Yunjing Intelligence (Shenzhen) Co., Ltd.**, Shenzhen (CN)

(72) Inventor: **Yang Li**, Dongguan (CN)

(73) Assignees: **Yunjing Intelligence Technology (Dongguan) Co., Ltd.**, Dongguan (CN); **Yunjing Intelligence (Shenzhen) Co., Ltd.**, Shenzhen (CN)

(**) Term: **15 Years**

(21) Appl. No.: **29/844,644**

(22) Filed: **Jun. 30, 2022**

(51) LOC (14) Cl. **15-05**

(52) U.S. Cl. .... **USPC D32/29**

(57) **CLAIM**

The ornamental design for a water tank for robotic vacuum cleaner, as shown and described.

DESCRIPTION

FIG. 1 is a front perspective view of a water tank for robotic vacuum cleaner showing my new design;
FIG. 2 is a rear perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

The dash-dash broken lines in the drawings depict the portions of the water tank for robotic vacuum cleaner which form no part of the claimed design.

1 Claim, 8 Drawing Sheets
